UNITED STATES PATENT OFFICE.

FRANÇOIS A. C. J. OMLOR, OF BONNEVOIE-LES-LUXEMBURG, LUXEMBURG.

FASTENING FOR GLOVES, &c.

SPECIFICATION forming part of Letters Patent No. 253,309, dated February 7, 1882.

Application filed December 19, 1881. (No model.)

To all whom it may concern:

Be it known that I, FRANÇOIS ADOLPHE CHARLES JEAN OMLOR, resident of Bonnevoie-les-Luxemburg, Grand Duchy of Luxemburg, 5 have invented a new and useful Improvement in Fastenings for Gloves and other Garments, which improvement is fully set forth in the following specification.

This invention has reference to the fastening 10 of gloves by means of a lace running through eyelets on opposite sides of the slit in the glove. Heretofore lacing has been employed for this purpose, although buttons are ordinarily used.

The present invention consists in the special 15 lace fastening hereinafter described, whereby the gloves, even when very long, can with the greatest ease be drawn on the hand and securely fastened.

The accompanying drawings, which form a 20 part of this specification, represent a glove provided with the improved fastening, Figure 1 showing the glove closed, and Fig. 2 the same closed at the wrist, but open at the top.

On each side of the slit in the glove is a row 25 of eyelets, *a*, through which the lace *b* is rove zigzagging across the opening. This lace is provided with a knot, *c*, at the inner end or bottom of the slit, and a hook, *d*, at the outer end. The length of the lace is such that the

30 glove can be opened, as shown in Fig. 2, without drawing the outer end through the eyelet. The hook *d* is adapted to prevent this end from being accidentally drawn through the eyelets; or a knot is made in the cord for the same purpose.

The knot *c* prevents the inner end of the lace being drawn through the bottom eyelet. Owing to the length of the lace there is a loose end where the glove is closed, as shown in Fig. 1. This end is wrapped around the 35 40 arm of the wearer and is secured by catching the hook *d* in the lacing.

At the wrist of the glove is a lace hook or button, *e*, over which the lace is caught. In

putting on or taking off the glove the bend of the lace is loosened from this button or lace-hook *e*. When the glove is on the lace is again slipped in place over the hook or button. 45

In place of the button or lace-hook other device which can be fastened and unfastened at will may be used. 50

The lace *b* may be elastic or inelastic. It is preferably made elastic, and the fastening then embodies also the invention subject-matter of my Patent No. 249,390, November 8, 1881. A separate lace could also be used for the button or lace-hook at the wrist of the glove, as shown in said patent. By using an elastic lace the lace itself lengthens, and it may be somewhat shorter than when an inelastic one is used, and consequently there is not so much 55 loose end when the glove is worn. 60

Instead of catching the hook at the outer end of the lace in the lace itself a special ring could be provided, or in place of a hook other suitable fastening device, a button, knot, loop, buckle, or the like could be used. The lace provided with a securing-hook at the end could also be used without the button or lace-hook at the wrist of the glove, if desired. 65

The invention is also applicable to garments other than gloves—as, for example, to the fastening of laced boots or shoes. 70

I claim—

The combination of the eyelets on opposite sides of the slit in the glove, the elastic or inelastic lace of a length as indicated, the lace hook or button at the wrist of the glove, and the hook or similar device at the end of the lace, substantially as described. 75

In testimony whereof I have signed this 80 specification in the presence of two subscribing witnesses.

FRANÇOIS ADOLPHE CHARLES JEAN OMLOR.
